CABINET FOR POPCORN MACHINES

Arthur D. Altemiller, Affton, Mo., assignor to Hercules Steel Products Corporation, Galion, Ohio, a corporation of Delaware

Application January 3, 1955, Serial No. 33,793

Term of patent 14 years

(Cl. D81—10)

Figure 1 is a front perspective view of a cabinet for popcorn machines illustrating my new design;

Figure 2 is a slightly reduced rear view thereof; and

Figure 3 is a slightly reduced view of the side not disclosed in Figure 1.

The stippled areas on the front panel and top indicate contrasting colored appearances.

I claim:

The ornamental design for a cabinet for popcorn machines, substantially as shown and described.
